NEEDLE THREADER

Walter Parsons, Brooklyn, N. Y.

Application January 14, 1942, Serial No. 426,665

3 Claims. (Cl. 223—99)

This invention relates to needle threaders and involves an improvement over the type shown in my Patent No. 2,115,999, dated May 3, 1938.

An object of the invention is to improve the structure shown in my prior patent and to simplify the operation of the device.

The particular object of this invention is to provide means for disengaging the thread from the threading hook after it has been drawn through the eye of the needle, so that the threaded needle may be removed from the feed shoot without danger of the hook unthreading the needle by pulling the thread from the eye.

Further objects of my invention will become more apparent as the description proceeds.

In the accompanying drawing—

Fig. 1 is a side elevation of an embodiment of my invention;

Fig. 2 is a side elevation in cross section;

Fig. 3 is a detailed sectional view showing the position of the parts as the needle is threaded;

Fig. 4 is a view similar to Fig. 3 showing the threading operation;

Fig. 5 is a sectional view showing the position of the parts after the operation has been completed;

Fig. 6 is a cross-sectional view taken on the line 6—6 of Fig. 3.

In the drawing I have shown the feed shoot encased in the figure of a bird, but this is purely for ornamental purposes and any suitable structure may be used.

My device includes a frame plate 10 which may be bent over at the bottom 11 to engage a clamp 12 so that the device may be positioned on a table or other member 13. To the upper edge 14 of the frame plate 12 there is attached a bent spring member 15 which may be integral with the frame member 10. The spring member 15 may be continued to form an arm 16 which is bent back upon itself to form the member 17, as shown in Fig. 6. This bent-back portion forms a channel 18 through which the upper end of the hook 19 is adapted to pass. The hook 19 is mounted on the upper end 20 of the frame plate 10.

Pivoted within the spring member 15 is a shoot member 25 which may be supported by a bushing or washer 26 through which a pin 27 extends. As shown in the drawing, the shoot member assumes the figure of a bird, but it will be understood that any suitable structure may be used.

Mounted in the shoot member 25 is the feed shoot 28 which may be more or less funnel-

shaped at its outer end 29 and reduced to a tube at the other end 30.

A plate 31 is pivoted at 32 to the frame plate 10 by means of a rivet pin or by any suitable means. Attached to the plate 31 is a stop member or guard plate 33 which is bent upon itself to surround the arm 16 and to extend above the arm 16 to protect the hook 19 and to govern the position of the needle. At the opposite end of the plate 31 is an arm 34 having at its outward end a hook 35. A pin 36 extends through the shoot frame 25 and the arm 34 slides on this pin until the hook 35 engages it.

In operation a needle 40 is placed in the shoot 28 with the tube 30 of the shoot in the downward position, as shown in Fig. 1. Naturally, the eye 41 of the needle must be inserted in the shoot first. The thread 43 is then placed in loop arrangement over the beveled edge 44 of the stop plate 33 and pulled downwardly. This action flattens the eye of the needle and causes the hook 19 to pass through the eye 41 and engage the thread 43, as shown in Fig. 3. It will be appreciated that this action is against the tension of the spring 15. As soon as the thread is released, the arm 16 will be returned by the spring 15 to the position shown in Fig. 4 with the hook 19 drawing the thread 43 through the eye 41 of the needle. It will be noted that in this position the hook 19 is resting in and covered by the channel 18. As the nose of the bird is raised, the bar 34 will slide on the pin 36 tipping the plate 31 on its pivot 32 to uncover the hook 19 as the thread is drawn farther through the eye 41. This will quickly disengage the thread 43 from the hook 19, as shown in Fig. 5, and the threaded needle may be removed from the tube 30 with the thread entirely free from the device.

I claim:

1. A needle threading device which includes a frame, a depressible spring plate mounted on said frame, a chute to receive and guide the needle to the proper position on the frame, said chute being pivotally mounted on the frame, a guide or stop plate disposed at the end of said spring plate to limit the movement of the needle, said stop plate being pivoted to the frame and having an arm extending over said spring plate, a pin upon said chute member, said arm being adapted to slide on said pin when said chute is pivoted on said frame.

2. A needle threader including a frame, a depressible spring plate mounted on said frame and adapted to support a needle, a hook mem-

ber mounted on said frame adjacent the end of said spring plate, a chute pivotally mounted on said frame, and a stop member pivotally mounted on said frame and surrounding said hook, said stop member having an arm in sliding engagement with said chute adapted to pivot said stop member when said chute is pivoted to uncover said hook.

3. In a needle threader, a frame, a hook

5 mounted on said frame, a spring plate on the other end of said frame bent upon itself to surround said hook, a chute member pivoted at one end of said frame, a stop plate pivoted to said frame, an arm on said stop plate slidably engaging said chute member and adapted to pivot said stop plate to uncover said hook when said chute member is pivoted.

WALTER PARSONS.
